UNITED STATES PATENT OFFICE.

ELHANAN L. MOODIE, OF NEW YORK, N. Y., ASSIGNOR OF ONE-HALF TO CHARLES H. GILLESPIE, OF SAME PLACE.

DESIGN FOR AN ADVERTISING-DISK.

SPECIFICATION forming part of Design No. 12,969, dated June 13, 1882.

Application filed April 29, 1882. Term of patent 3½ years.

To all whom it may concern:

Be it known that I, ELHANAN L. MOODIE, a citizen of the United States, residing in the city and county of New York, in the State of New York, have invented and produced a new and original Design for Advertising or Ornamental Easels or Disks, of which the following is a specification, reference being had to the accompanying drawing or pictorial representation, forming a part thereof, and which is a front view representing my said design.

The leading feature of my design consists in a novel, graphic representation of the plate or face of an "easel" or "disk," so termed, designed for advertising or ornamental purposes, the same comprising the representation of a human face surrounded by the representation of the circumferential portions of a sunflower, or, in other words, in the representation of a sunflower having superposed upon the center thereof the representation of a human face. Thus, for example, at the center is the representation of the human face, which may be represented as having a veil or wrap around the same, or with any suitable coiffure, or which, when preferred, may be entirely devoid of such ornamental adjuncts; and surrounding said representation is the representation of the circumferential or petal portions of a sunflower, as represented at A. The surface of said plate or face may be appropriately colored in tints corresponding to those of the human face and to those of the tint of the petals of a sunflower.

What I claim as my invention is—

The design for an advertising or ornamental easel or disk, substantially as herein shown and described, the same being composed of the representation of a human face surrounded by the circumferential or petal portions of a sunflower, substantially as described.

ELHANAN L. MOODIE.
